UNITED STATES PATENT OFFICE.

FERDINAND FRÉCHETTE, OF NOTRE DAME DE CHARNY, QUEBEC, CANADA.

GRATE.

No. 906,521.

Specification of Letters Patent.

Patented Dec. 15, 1908.

Application filed February 7, 1908. Serial No. 414,806.

To all whom it may concern:

Be it known that I, FERDINAND FRÉCHETTE, a subject of the King of Great Britain, residing at Notre Dame de Charny, 5 county of Levis, in the Province of Quebec, Canada, have invented certain new and useful Improvements in Grates; and I do hereby declare that the following is a full, clear, and exact description of the invention, such as 10 will enable others skilled in the art to which it appertains to make and use the same.

The present invention relates to grates and grate bars for furnaces, large heating plants and the like, and more particularly to grates 15 and grate bars, such as are used in steam boiler furnaces and the like.

It is designed with the idea of having a plurality of hollow grate bars communicating with one another through passages in supports 20 upon which the opposite ends of the bars are carried, the passages in the supports being provided with valves so disposed as to enable the ready removal of any one or more of the grate bars, while at the same time retaining a full amount of water in the remaining bars and in the passages of the supports. 25 A grate so constructed acts both as a preliminary heater for water passing to the boiler, and as a cooler to prevent overheating 30 of the separate parts.

In order to enable one skilled in the art to which the present invention relates to the more readily understand the construction, operation and use of the same, reference 35 should be had to the accompanying drawings, forming part of the present application.

In the several figures, like reference characters designate the same parts throughout.

In the drawings: Figure 1 is a plan view of 40 a section of a grate and its supports, showing the invention; Fig. 2 is a partial longitudinal section through one of the grate bars and one support, showing the circulation; and, Fig. 3 is a longitudinal section through a part of one 45 of the end supports.

Each of the grate bars 1 is cast or bored to form a longitudinal conduit 2, through which water may pass freely from one support or head 3 at one end to a companion support at 50 the opposite end. The under faces of these bars near their opposite ends are provided with vertical passages 4, which communicate with the conduits 2. The supports 3 are each provided with a plurality of wells or 55 vertical bores 5, the bores being separated into pairs and the separate wells of each pair

being connected by horizontal passages 6, one well of each pair being provided with a tubular removable two-way valve 7. This valve is provided with an opening 8 adapted 60 to register with the passage 6, and in this position to allow the free flow of water from one well of the pair to the next well. These valves are all held in place against the water pressure by means of the removable cap plate 65 9, which may be secured in any suitable way as desired.

One particular feature of the invention is the alternate arrangement of the valves 7 relatively to the opposite ends of the grate bars. 70 Thus a valve in one support will be directly beneath and in communication with the vertical passage 4 of one grate bar, while the vertical bore in the opposite end of the same bar will be over a well 5 which does not contain a 75 valve, but which communicates through a passage 6 with a well having a valve, which second well communicates through a second passage 4 with the conduit 2 of the next grate bar 1. Thus when a grate bar is 80 broken or has to be removed for any reason, it is only necessary to turn the valve 7 at the opposite ends of the bar to be removed and the adjacent bar, so as to cut off passage of water between these two valves. Thus any 85 one or more of the bars may be cut off from the circulation and removed and replaced by other bars. At the same time, the grate bars on either side of the one removed will be 90 retained full of water, as will be readily understood.

In order to catch and direct the inrushing air beneath the grate so that it will be evenly distributed instead of all rushing to the back and rising at one point, the bars are provided 95 with vane sections 10, which curve downwardly and forwardly toward the front end of the grate to deflect the air as it rushes into the ash pit beneath the grate. These vane sections are so disposed as to aline themselves to form substantially parallel vanes extending across the under sides of the grate and running transverse to the grate bars.

The water may be let into one end of one 105 of the supports through an inlet pipe 11 if desired, and after passing through the several grate bars and passages, may be drawn off through the outlet 12 coupled to a suitable pipe. If desired, the passage 12 may be connected to a boiler or heating system, 110 the grate bars acting either as a main heating device or as a preliminary heating device,

and the water being passed continuously around through the system and grate. Or it may be used as a grate and the circulation of water maintained to keep the grate cool.

5 Many changes in the construction and arrangements of these parts, and many other applications of the device as a whole may be had, without in any way departing from the field and scope of the invention, and it is 10 meant to include all such within the present application, wherein only one preferred form has been shown to more clearly illustrate the same.

Having thus fully described my invention, 15 what I claim as new, and desire to secure by Letters Patent, is:—

In a grate of the character described, a plurality of grate bars each provided with a longitudinal conduit, supports upon which 20 the opposite ends of each grate bar are adapted to be mounted, wells in said sup-

ports, passages in said grate bars communicating with the aforesaid conduits therein and with said wells, passages in the supports connecting said wells in pairs, means for delivering water to and from said supports, and a valve in one well of each pair of wells adapted to control the flow of water through each well of the pair, the valves in the two supports alternating with one another in 25 such manner that the valve of one support will lie beneath the end of one grate bar while the valve of the opposite support will lie beneath the opposite end of the next adjacent grate bar.

30 In witness whereof I have hereunto set my hand in the presence of two witnesses.

FERDINAND FRÉCHETTE.
